United States Patent Office.

WILLIAM W. EASTMAN, OF MEADVILLE, PENNSYLVANIA.

Design No. 4,791, dated April 11, 1871.

DESIGN FOR A FLANGE AND CRANK.

The Schedule referred to in these Letters Patent and making part of the same.

To all whom it may concern:

Be it known that I, WILLIAM W. EASTMAN, of Meadville, in the county of Crawford and State of Pennsylvania, have invented and produced certain new and useful Improvements in Designs for Flange and Crank-Patterns for rig-irons for boring artesian wells, and for other purposes; and the following is a full, clear, and exact description of the same, reference being had to the accompanying drawing making a part of this specification, in which—

Figure 1 represents a perspective view of my new-design crank-pattern, with a wrist-pin in one of the series of holes, forming a crank when secured on the end of a shaft; also a face view of one of the pair of flanges on the shaft.

Figure 2 shows the inside view of one of the circular flange-patterns on the shaft, and the reverse view of the crank-pattern.

The advantages of my improved patterns for casting the crank and flanges for rig-irons, as shown in the two figures as above described, are that they may

be made at least one-third lighter than those made without a recess on the inside, and ribs and bosses on their face or outside, (in other words, plain,) and they can be fitted and turned off true on the inside of the flanges in one-half of the time and at half of the usual cost of plain solid castings.

My design patterns are otherwise more desirable, and are in such demand where they are in use and have become known that no others are used or can be sold when these can be obtained.

What I claim as my invention, and desire to secure Letters Patent for, is—

The design for patterns for casting "rig-irons" for boring artesian and oil-wells, and for other purposes, as shown and described.

In testimony whereof I hereunto subscribe my name.

WM. W. EASTMAN.
